UNITED STATES PATENT OFFICE.

HOMER L. ARNOLD, OF ARCATA, CALIFORNIA.

DIRECTION INDICATOR.

Application filed October 2, 1922. Serial No. 591,909.

To all whom it may concern:

Be it known that I, HOMER L. ARNOLD, a citizen of the United States, residing at Arcata, in the county of Humboldt and State of California, have invented new and useful Improvements in Direction Indicators, of which the following is a specification.

This invention relates to improvements in direction indicators, and is particularly adapted to be secured to the wind shield of an automobile for the purpose of informing others of the direction that the car is to be maneuvered.

The principal object of this invention is to provide a device of this character which is extremely simple in construction, cheap to manufacture and therefore well within the purchase price of the average user.

Another object is to provide an indicator which is neat in appearance, simple to attach to the car and one which may be relied upon as being fool proof.

A further object is to provide an indicator which is visible at all times either day or night, and one which may be operated entirely from a point within the vehicle thereby obviating the necessity of raising storm curtains or the like during inclement weather.

30 Other objects and advantages will be apparent during the course of the following description.

In the accompanying drawings forming a part of this specification, and in which like numerals are employed to designate like parts throughout the same,

Figure 1 is a rear elevation of my device partly in cross-section,

Figure 2 is a top plan view of my device partly broken away for the purpose of disclosing the interior of the signal, and

Figure 3 is a detail view of a screen-like member having indicating letters secured thereon.

45 Applicant is aware of the fact that various forms of signals have been placed upon the market, but these signals are very expensive to install, complicated in construction and therefore easily deranged, or they do not comply with the requirements of the State laws, with the result that they are not of universal value.

In my construction, I have sought to provide a structure which may be easily seen either day or night, one which may be ad-

justed to meet State requirements, and one which is simple and therefore reliable.

In the accompanying drawings wherein for the purpose of illustration is shown a preferred embodiment of my invention, the numeral 5 designates the glass of the wind shield, while the numeral 6 designates the metal standard for retaining the glass 5. To this standard, I secure a clamp formed by the numerals 7 and 8 which are secured together as by a bolt 9. These clamps serve to support a tubular portion 11, which projects outwardly from the support 6 and is bent at right angles as shown at 12 and proceeds toward the rear of the car so as to form a hub as shown at 13 for a drum 14. This drum is in the form of a hollow casing to which is secured a pulley 16. This pulley is provided with a pin 17 which is adapted to contact a pin 18 secured in the tubular member 11. In order to keep these pins 17 and 18 normally in contact one with the other, I provide a spring 19 having one end in contact with a pin 21, carried upon one surface of the drum 14 and having its opposite end coiled about the hub 13 and secured about a pin 22 secured to the hub 13. A cable 23 is secured as shown at 24 to the pulley 16 and extends thereabout and is adapted to lie over a hook 26 formed upon the clamp member 8. This cable 23 has secured thereon rings as shown at 27, 28 and 29, the purpose of which will be later seen. At 31, I have shown a lamp preferably an electric lamp, which receives current through the medium 90 of a cord 32 passing through the tubular member 11. This lamp serves to illuminate the interior of the drum 14 and to shine through the window 33 formed in the drum as best shown in Figure 1. Mounted within the drum and secured upon the hub 13 is a segmental member 34. This member 34 is preferably made of wire gauze as shown in Figure 3 and has secured thereto a portion 36 formed of solid metal to act as a blind. Secured upon the wire gauze are suitable spaced letters as shown at 37, 38, 39 and 41, which letters may be formed in any convenient manner.

The operation of my device is as follows:—

Assuming that my device has been placed upon the wind shield of a car, and the parts are in the position shown in Figure 1, the indication will be that the car is proceeding

in its course and is not going to execute any particular maneuver. Should the operator desire to turn toward the right, he will grasp the ball A secured to the cord 23, lift it out of its engagement with the hook 26, give it a pull until the ring 29 lies upon the opposite side of the hook 26 from that upon which it normally lies. When the operator releases the ball A, the cord will move so 10 as to cause the ring 29 to abut the hook 26 which will hold the drum in a position so as to expose the letter R upon the wire segmental gauze member 34, it being understood that the drum 14 has revolved through 15 its connection with the pulley 16 about which the cord 23 is wound.

It will be seen that by causing either of the rings 27 or 28 to engage the hook 26 a different letter will be brought into view. 20 The drum will rotate in the direction of the arrow an amount in proportion to the movement of the cable 23.

For night driving, the lamp 31 is illuminated, with the result that the light shines 25 through the wire gauze and causes the letters to stand out in bold relief thereby providing a visible warning.

It is obvious that two gauze plates might be employed, one upon each side of the 30 light, in which instance a window would be provided on each side of the drum, which would give a warning to oncoming vehicles as well as those coming from the rear.

It is to be understood that the form of my invention herewith shown and described is to be taken as a preferred example of the same, and that various changes in the shape, size and arrangement of parts may be resorted to without departing from the spirit of the invention or the scope of 40 the subjoined claim.

Having thus described my invention, I claim:—

In a device of the character described, the combination with a support, a tubular member extending outwardly from said support and having a hub portion thereof formed at right angles thereto, a drum rotatably mounted on said hub, a window formed in said drum, a pulley secured to said drum, a cable having one end secured to said pulley and extending thereabout, said cable extending to a point remote from said drum, rings secured to said cable for the purpose of retaining said cable in adjusted position, a spring coiled about said hub and having its opposite end abutting a pin mounted on said drum, a segmental member mounted upon said hub and within said drum, said segmental member being 55 formed of wire gauze, characters formed on said segmental member, and means for illuminating the interior of said drum.

In testimony whereof I affix my signature.

HOMER L. ARNOLD.
